Ashton

UNITED STATES PATENT OFFICE.

ORRELL ASHTON, DECEASED, LATE OF SWAMPSMOTT, MASSACHUSETTS, BY HANNAH ASHTON, EXECUTRIX, OF WOLLASTON, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

PULLING-OVER MACHINE.

Application filed November 2, 1916, Serial No. 129,216. Renewed June 24, 1922. Serial No. 570,720.

To all whom it may concern:

Be it known that ORRELL ASHTON, late of Swampscott, in the county of Essex and State of Massachusetts, deceased, invented 5 certain Improvements in Pulling-Over Machines, of which the following description, in connection with the accompanying drawings, is a specification, like reference characters on the drawings indicating like parts 10 in the several figures.

This invention relates to machines for use in the manufacture of boots and shoes for pulling the upper over the last, and in some aspects has more particular reference to 15 pulling-over machines for use in the manufacture of turn shoes. An important object of the invention is to facilitate the relative manipulation of the upper proper and the lining in the pulling-over operation on 20 turn shoes, to the end that in the manufacture of such shoes as are provided with tips the tip may be readily straightened, and to the further end that the lining in turn shoes may be laid smoothly over the upper in such 25 manner as to avoid the presence of lining wrinkles after the shoe is turned.

In one method of procedure in the pulling-over of turn shoes the upper and the lining are both entered in the grippers when 30 the work is presented to the machine and are pulled over the last together. If the shoe is provided with a tip, however, the fact that the lining, which is on the outside of the upper at this stage, conceals the tip 35 seam makes it difficult to adjust the upper in such manner as to insure the correct location of the tip line. As an alternative course, the upper alone is sometimes pulled by the grippers, while the lining is free to 40 be turned back at the toe to reveal the tip seam, and after the upper has been pulled the lining is smoothed over the upper by hand and is then forced in over the margin 45 of the sole together with the upper and fastened in position. It is difficult, however, in this method of procedure to cause the lining to be drawn tightly enough over the upper to avoid the presence of wrinkles in 50 the lining after the shoe is turned.

With the object, among others, of eliminating the above mentioned difficulties, this invention provides novel means for operating upon the shoe materials in such manner

as to leave the lining substantially free from tension during the upper pulling operation 55 and subsequently to conform the lining smoothly to the contour of the upper. The lining is thus left free to be turned back at the toe to reveal the tip seam at the time when adjustment of the upper is effected. 60 The illustrative embodiment of the invention comprises a lining engaging device movable over the lining on the forepart of the shoe in the direction of the shoe bottom in such manner as to replace the lining in 65 position if the lining has been turned back to reveal the tip seam, the device being maintained in effective engagement with the lining to cause it to conform the lining smoothly and tightly to the contour of the 70 upper on the last. The device shown comprises wipers for engaging the lining frictionally at opposite sides of the forepart of the shoe and treadle means for operating the wipers. It should be understood, however, 75 that the drawings show but one of a variety of construction in which the invention, in its broader aspects, may be embodied.

The above and other novel features of the invention, including certain details of construction and combinations of parts, will 80 now be described with reference to the accompanying drawings and pointed out in the claims.

In the drawings:

Fig. 1 is a view in side elevation of a portion of a pulling-over machine in which the invention is embodied.

Fig. 2 is a view in front elevation of a portion of the mechanism shown in Fig. 1.

Fig. 3 is a view similar to Fig. 1 of a shoe and adjacent mechanism, illustrating the final stage in the manipulation of the lining engaging device, and

Fig. 4 is a section on the line 4—4 of Fig. 1.

The mechanism provided in accordance with this invention is shown as applied to a pulling-over machine of a well known type, comprising the usual standard 2, heel 100 rest 4, sole rest 6, side grippers 8 and toe gripper 10. Positioned for movement over the bottom of the shoe are also the usual overlaying and tacking devices 11 which serve to lay the upper materials over the 105 margin of the sole and fasten them in posi-

tion. Attached to the machine below the position occupied by the shoe as determined by the heel rest 4 and the sole rest 6 is the device for operating upon the shoe lining, comprising two metal plates 12 mounted on the upper ends of rods 14 the lower ends of which are clamped to a bracket 16 mounted in turn for sliding movement vertically on rods 18 to the lower ends of which 10 is connected a treadle 20. A clamp 22 on the standard 2 supports rigidly a holder 24 provided with hooks 26 which partially embrace the rods 18 and serve as guides for the rods. Additional guiding means for 15 the rods 18 in their reciprocating movement is provided by bars 28 and 30 clamped adjustably in a holder 32, the bar 28 being hooked for engagement in a hole in a plate 34 secured to the upper ends of the 20 rods 18 and the bar 30 being pivoted on a strap 36 on the standard 2. The upper guiding device comprising the bars 28 and 30 will thus turn about the pivotal connection of the bar 30 with the strap 36 during 25 the reciprocatory movement of the rods 18.

Each of the rods 18 carries a spring 38 which rests upon a collar 40 on the rod. These springs serve as bumpers for the 30 bracket 16 and thus support the rods 14 in their lowermost position. Slidably mounted on the rods 18 is also a holder 42 which is clamped by means of a screw 44 to one of the rods 14 and will therefore move with the 35 rods 14 as the latter are raised or lowered. A plate 46 on the rear of the holder 42 carries pins 48 which enter holes in the rear of the holder and bear at their inner ends on the rods 18. A bolt 50 is secured to the 40 plate 46, and a spring 52 bearing at one end on the front of the holder 42 and at its other end on a nut 54 on the end of the bolt acts through the bolt and the plate 46 to hold the ends of the pins 48 against the rods 18. Near 45 their upper ends the rods 18 have recesses 56 which receive the pins 48 when the rods 14 are moved to their uppermost position on the rods 18. This is a preliminary movement imparted by hand to the rods 14 to bring the members 12 into position to become effective upon the lining of the shoe upon the subsequent operation of the treadle 20. The approximate position attained by the 50 members 12 in this preliminary movement is indicated in dotted lines in Fig. 1.

The holder 42 in the end opposite to that in which the clamping screw 44 is located is provided with a slot 58 in which the rod 14 on that side is received. Springs 60 connected to the opposite rods 14 tend to swing the rods toward each other, the rods being sufficiently yielding to permit such relative movement. The limit of movement of the rods, and consequently of the members 12, 55 toward each other is adjustably determined

by means of a screw 62 which is threaded in a holder 64 clamped to one rod 14, the head of the screw being positioned for engagement with the other rod. The wipers 12 will be positioned, by adjustment of the screw 62 70 in accordance with the size of the shoe, to cause them to engage the upper materials firmly when they have been raised preliminarily to the proper height to cause the pins 48 to enter the recesses 56, as shown by 75 dotted lines in Fig. 1, and in the subsequent movement of the wipers effected by the operation of the treadle 20 they will be spread apart against the tension of the springs 60 while moving over the wider portions of the 80 shoe toward the shoe bottom.

The wipers 12 are mounted on holders 66 pivoted at 67 in the upper ends of the rods 14, and springs 68 connected respectively to the holders and to the rods tend to position 85 the wipers normally in parallel relation as shown in Fig. 2 while permitting them to turn as they move over the shoe in such manner as to follow the contour of the shoe. It is preferable to provide the wipers 12 with 90 a covering of some material such as to insure a good frictional contact with the lining, and in the construction shown, for example, the wipers have a covering of emery cloth. 95

In the use of the construction shown, the shoe will be presented in the position indicated and the upper entered in the toe and side grippers, the lining being left free in order to permit it to be turned back at the 100 toe to reveal the tip seam. The operator by observing the tip seam, is thus enabled to determine readily at what particular points the side grippers should engage the upper. After the upper has been entered properly in 105 the grippers the machine is started and the grippers are operated to pull the upper, the machine then coming to rest in the usual way with the upper under tension. The tip seam, still within view, enables the operator 110 then to determine whether any relative adjustment of the opposite sides of the upper is necessary in order to position the tip line in the correct angular relation to the last. If adjustment is necessary it is effected in the 115 well known manner by relative movement of the opposite side grippers. While the upper is still held under tension the operator will then slide the rods 14 upward by hand until the pins 48 snap into the recesses 56, thus positioning the wipers 12 as indicated by dotted lines in Fig. 1, and will then depress the treadle 20, forcing the wipers farther upward in a direction which, by reason of the 120 position of the shoe, is diagonally toward the bottom edge and toe end of the shoe, the operator's hands being left free during this 125 treadle effected movement to assist the wipers in laying the lining smoothly over the upper or to perform any other operation 130

that may be required. Through this movement of the wipers the lining will be replaced in its proper position and conformed smoothly and tightly to the contour of the 5 pulled upper ready to be laid over the margin of the sole and fastened with the upper in the subsequent operation of the overlaying and tacking devices 11 which, as shown, may include end embracing wiper plates to 10 wipe the margin of the upper materials into lasted position. While holding the wipers 12 at the limit of their upward movement adjacent to the grippers the operator will then cause the machine to complete its cycle of 15 operations in which the upper and the lining will be wiped inwardly together over the margin of the sole and fastened. When it is desired to remove the shoe from the machine the treadle will be released, the pins 20 48 will be disengaged from the recesses 56 by pressing on the bolt 50, and the rods 14 will be lowered until the bracket 16 engages the bumper springs 38. While the invention is herein illustrated by reference to turn 25 shoe work, it will be evident that in some of its aspects it is not limited in utility to the manufacture of that particular type of shoe.

Having described the invention, what I 30 claim as new and desire to secure by Letters Patent of the United States is:

1. A turn shoe pulling-over machine having, in combination, means for pulling an upper into conformity to the shape of the forepart of a last while the lining of the shoe 35 is substantially free from tension, and means constructed and arranged to engage the lining at the sides of the shoe between the bottom edge and the top of the last and wipe the lining over the tensioned portion of the 40 upper to conform it to the contour of the upper on the last.

2. A turn shoe pulling-over machine having, in combination, means for pulling an upper into conformity to the shape of the 45 forepart of a last while the lining of the shoe is substantially free from tension, members mounted for movement over the lateral periphery of the last in paths independently conformable to the contour of the upper at 50 opposite sides of the last and arranged to engage the lining at the sides of the shoe remote from the bottom edge of the last and to wipe the lining over the upper into conformity to the contour of the upper on the last, and 55 mechanism for operating said members while the upper is held under tension by the pulling means.

3. A turn shoe pulling-over machine having, in combination, power operated means 60 for pulling an upper into conformity to the shape of the forepart of a last while leaving the lining substantially free from tension, means movable over the lining of the shoe on the lateral periphery of the last to conform 65 it to the contour of the upper on the last, and

treadle mechanism for operating said last named means while the upper is held under tension by said power pulling means.

4. A turn shoe pulling-over machine having, in combination, means for pulling an 70 upper over the forepart of a last while the lining of the shoe is displaced to reveal the tip seam of the upper, and means constructed and arranged for movement in a direction transverse to the plane of the shoe bottom to 75 replace the lining.

5. A turn shoe pulling-over machine having, in combination, power operated means for pulling an upper over the forepart of a 80 last while the lining of the shoe is turned back from the toe to reveal the tip seam of the upper, wipers movable in engagement with the lining in a direction toward the plane of the bottom of the last to replace the lining and conform it to the contour of the 85 upper, and manual means for operating said wipers after the upper has been pulled.

6. A turn shoe pulling-over machine having, in combination, means for pulling an upper alone over a last at the forepart, and 90 means mounted for movement over the lining at the side of the shoe diagonally toward the bottom and the toe end of the last to conform the untensioned lining to the contour of the upper on the last after the upper has 95 been pulled.

7. A turn shoe pulling-over machine having, in combination, side grippers for engaging and pulling an upper over the opposite sides of the forepart of a last while the lining is turned back to reveal the tip seam of the upper, and means mounted for movement 100 subsequently over the lateral periphery of the shoe toward positions adjacent to said side grippers to replace the lining. 105

8. A turn shoe pulling-over machine having, in combination, grippers for engaging and pulling an upper over a last while the lining is turned back at the toe to reveal the tip seam of the upper, tackers for fastening 110 the upper, and means mounted for movement over the lateral periphery of the shoe toward the edge of the shoe bottom for engaging portions of the lining in their turned-back position and moving them into position to 115 be operated upon by the tackers in the fastening operation.

9. A turn shoe pulling-over machine having, in combination, means for pulling an upper over a last, wipers for engaging the 120 lining at opposite sides of the shoe and wiping the lining toward the bottom edge of the last into conformity to the contour of the upper, and treadle mechanism for operating said wipers. 125

10. A turn shoe pulling-over machine having, in combination, means for pulling an upper over a last positioned bottom upward, means for wiping the lining over the upper, said wiping means being positioned normally 130

below the shoe, and treadle mechanism for raising the wiping means in engagement with the lining to cause said means to wipe the lining over the upper.

5 11. A turn shoe pulling-over machine having, in combination, means for pulling an upper over a last, wipers comprising substantially flat plates arranged with their side faces toward the shoe and positioned for 10 movement over the lining on the lateral periphery of the shoe at opposite sides of the shoe to wipe the lining into conformity to the contour of the upper, means for operating said wipers, and means for holding the 15 wipers yieldingly in contact with the lining during their engagement with the lining.

12. A turn shoe pulling-over machine having, in combination, means for pulling an upper over the forepart of a last, wipers for 20 engaging the lining at opposite sides of the shoe, means for moving the wipers over the lining to conform it to the contour of the tensioned upper, and yielding means tending to move said wipers relatively toward each 25 other while permitting them to be forced apart by wedging action of the shoe to cause them to follow the contour of the upper on the last.

13. A turn shoe pulling-over machine having, in combination, means for pulling an upper over a last and for holding it under tension at the opposite sides of the forepart, wipers for engaging the lining at opposite sides of the shoe, means for moving said 30 wipers from a position adjacent to the top of the forepart of the shoe toward the bottom edge of the last, and yielding means for positioning the wipers normally at a distance apart less than the width of the forepart of the shoe while permitting them to 35 separate as they move over the shoe.

14. A turn shoe pulling-over machine having, in combination, means for pulling an upper over a last, wipers movable over the 40 lining at opposite sides of the shoe to conform the lining to the contour of the upper, yielding means tending to move said wipers relatively toward each other, and means for 45 adjustably limiting said relative movement 50 of the wipers.

15. A turn shoe pulling-over machine having, in combination, means for pulling an upper over a last, rods movable lengthwise toward or from the last in directions transverse to the plane of the bottom of the last, wipers on said rods for engaging the lining of the shoe, and means for operating the rods to cause said wipers to conform the lining to the contour of the upper.

60 16. A turn shoe pulling-over machine having, in combination, means for pulling an upper over a last, rods movable lengthwise toward or from the last, wipers on said rods for engaging the lining of the shoe, a spring 65 between the rods tending to position the

wipers relatively near together, and means for operating the rods to cause the wipers to conform the lining to the contour of the upper.

17. A turn shoe pulling-over machine having, in combination, means for pulling an upper over an inverted last, rods positioned substantially upright below the last, wipers on said rods for engaging the lining of the shoe, and treadle mechanism for raising the rods to cause the wipers to wipe the lining into conformity to the contour of the upper.

18. A turn shoe pulling-over machine having, in combination, toe and side grippers and means for operating them to pull an upper over a last and to hold it under tension while the lining of the shoe is turned back to reveal the tip seam of the upper, means movable over the lining in a direction transverse to the plane of the shoe bottom to replace it in position while the upper is under tension, and mechanism for operating said replacing means constructed to position said means normally remote from the shoe while permitting said means to be moved initially toward the shoe prior to the operative movement of said mechanism.

19. A turn shoe pulling-over machine having, in combination, means for pulling an upper over a last while the lining of the shoe is turned back to reveal the tip seam of the upper, means movable over the lining of the shoe to replace it in position while the upper is under tension, an operating member, and connections between said member and replacing means including parts relatively movable to permit said means to be moved initially toward the shoe in the direction of its operative movement prior to its operation by said member.

20. A turn shoe pulling-over machine having, in combination, means for pulling an upper over a last while the lining of the shoe is turned back to reveal the tip seam of the upper, wipers movable over the lining to replace it in position while the upper is under tension, an operating member, and connections between said member and wipers including parts relatively movable to permit the wipers to be positioned normally remote from the shoe and to be moved initially into substantial engagement with the lining prior to their operation by said member.

21. A turn shoe pulling-over machine having, in combination, means for pulling an upper over a last, wipers movable over the lining of the shoe in the direction of the bottom of the last, an operating member, connections between said member and wipers comprising rods relatively extensible to permit the wipers to be moved initially toward the shoe prior to their operative movement, and means for locking said rods in their extended relation.

22. A turn shoe pulling-over machine hav-

ing, in combination, means for pulling an upper over a last, wipers movable over the lining of the shoe in the direction of the bottom of the last, a treadle for operating said wipers, and connections between said treadle and wipers comprising rods relatively movable lengthwise to permit the wipers to be positioned normally a substantial distance below the shoe and to be raised substantially

10 into engagement with the lining prior to their operation by the treadle.

23. A machine for shaping to a last turn shoe materials comprising an upper and a lining having, in combination, means for pulling the upper over the last and for holding it under tension while leaving the lining substantially free from tension, means for engaging frictionally a portion of the lining between the bottom edge and the top 20 of the last, and mechanism for operating said lining engaging means to wipe the lining into conformity to the contour of the upper while the upper is held under tension by said pulling means.

25. 24. A machine for shaping to a last turn shoe materials comprising an upper and a lining having, in combination, power means for pulling the upper over the last and for holding it under tension while leaving the lining substantially free from tension, and means constructed and arranged for manual operation while the upper is held under tension by said pulling means to engage the lining frictionally on the lateral periphery 30 of the shoe and wipe it toward the bottom edge of the last into conformity to the contour of the tensioned upper.

25. A machine for shaping to a last turn shoe materials comprising an upper and a lining having, in combination, means for pulling the upper over the last while leaving the lining substantially free from tension, means for fastening the upper and the lining to the sole, and means constructed and arranged for operation while the upper is under tension to wipe the lining over the lateral contour of the last and to hold it in position to be operated upon by said fastening 45 means.

50. 26. A machine for shaping to a last turn shoe materials comprising an upper and a lining having, in combination, means for pulling the upper over the last and holding it under tension while leaving the lining 55 free to be displaced to reveal the tip seam of the upper, means for fastening the upper and the lining to the sole, and means constructed and arranged for operative movement over the lateral periphery of the last prior to the operation of said fastening means to replace the lining and conform it to the contour of the upper.

27. A machine for shaping to a last turn shoe materials comprising an upper and a 60 lining having, in combination, means for

gripping the forepart of the upper and pulling it over the last while leaving the lining free to be turned back at the toe to reveal the tip seam of the upper, means for overlaying and fastening the upper and the lining 70 on the sole, and means for moving the turned back portion of the lining into position to be operated upon by the overlaying and fastening means.

28. A machine for shaping to a last turn shoe materials comprising an upper and a lining having, in combination, means for pulling the upper over the forepart of the last while leaving the lining at the forepart substantially free from tension, means constructed and arranged for movement over the lining toward the plane of the bottom of the last while the upper is under tension to conform the lining to the contour of the upper, and members mounted and controlled independently of said lining engaging means for subsequent operation to lay the margin of the upper and lining inwardly over the bottom of the last.

29. A machine for shaping to a last turn shoe materials comprising an upper and a lining having, in combination, power operated means for pulling the upper over the last at the toe and at opposite sides of the forepart and for holding it under tension while leaving the lining free to be turned back to reveal the tip seam of the upper, means mounted for movement toward the bottom of the last in frictional engagement with the lining to replace the lining and conform it to the 100 contour of the upper, and operating mechanism for said lining engaging means constructed and arranged to permit said means to be located in a position relatively remote from the shoe during the upper pulling operation and then to be positioned manually substantially in engagement with the lining prior to the operation of said mechanism.

30. A machine for shaping to a last turn shoe materials comprising an upper and a lining having, in combination, means for gripping the upper alone at the toe end and at opposite sides of the forepart and for pulling it over the last, means for engaging the lining at spaced intervals on the lateral 110 periphery of the last, and mechanism for moving said lining engaging means over the lining toward the bottom edge of the last to conform the lining to the contour of the upper.

31. A machine for shaping to a last turn shoe materials comprising an upper and a lining having, in combination, means for gripping the upper alone and for pulling it over the last, means for subsequently conforming the lining to the contour of the upper comprising members for engaging the lining at the opposite sides of the last while leaving the lining free round the end of the shoe, and operating mechanism for moving 125 130

said members over the lateral periphery of the shoe toward the edge of the last bottom in a determinate path with a component of movement toward the toe end of the shoe.

32. In a machine of the class described, the combination with means for pulling an upper over the forepart of a last, of means arranged to engage the upper materials at the opposite sides of the forepart of the last and to move over the lateral periphery of the shoe toward its bottom edge to conform said materials to the contour of the last, and spring means for holding the opposite side portions of said conforming means yieldingly in pressing engagement with the shoe while permitting them to be spread apart by wedging action of the shoe.

33. In a machine of the class described, the combination with means for positioning

an upper and a last and means for working 20 the margin of the upper inwardly over the bottom of the last, of members mounted and controlled independently of said over-working means and arranged to engage the upper materials at the opposite sides of the forepart of the last and to move over the lateral periphery of the shoe toward its bottom edge to conform said materials to the contour of the last, and spring means arranged to press 25 said members yieldingly against the opposite sides of the shoe while permitting them to be spread apart by wedging action of the shoe during their operative movement.

In testimony whereof I have signed my name to this specification.

HANNAH ASHTON,
*Executrix of the will of Orrell Ashton,
deceased.*
